UNITED STATES PATENT OFFICE.

PETER McNAUGHTON, OF CHARLOTTE, MICHIGAN.

PLOW.

SPECIFICATION forming part of Letters Patent No. 663,977, dated December 18, 1900.

Application filed October 1, 1900. Serial No. 31,700. (No model.)

To all whom it may concern:

Be it known that I, PETER McNAUGHTON, a citizen of the United States, residing at Charlotte, in the county of Eaton and State of Michigan, have invented a new and useful Plow, of which the following is a specification.

My invention is an improved plow, and relates particularly to the beam and to means for adjusting the same so that its front end 10 may be raised and lowered and for securing the beam at any desired adjustment, thereby enabling the plow to be used in either hard or soft ground and to be run at any desired depth in the soil.

15 My invention consists in the peculiar construction and combination of devices herein-after fully set forth and pointed out in the claims.

In the accompanying drawings, Figure 1 is 20 an elevation of a plow embodying my improvements, a portion of the moldboard and one of the handles being removed. Fig. 2 is a detail view of the same, partly in section, on the plane indicated by the line *a-a* of Fig. 1. Fig. 25 3 is a detail perspective view of the locking and adjusting cam.

In the embodiment of my invention here shown the beam 1 of the plow is curved in the usual manner and formed integrally with the 30 standard 2, which standard bears against the inner side of the landside-plate 3 of the plow and is pivotally connected thereto by a bolt 4, which passes transversely through an opening in the heel of the standard and is secured 35 in the opening in the landside-plate. The latter is further provided with an adjusting-slot 5, which is curved and is concentric with the axis of the pivotal bolt 4. A bolt 6 is disposed in an opening in the said standard 40 which registers with said slot 5, and said bolt operates in said slot and is provided with the usual tap or nut 7, by means of which the beam may be set at any desired adjustment. A disk 8 is journaled on a bolt 9 and bears 45 against the rear side of the standard or downturned rear portion of the beam; the said disk being adapted to be partly rotated on the said bolt 9, and the said disk is provided on its front side with a cam 10, the front side of 50 which is curved and is eccentrically disposed on the disk. The shape of the said cam is such that the front portion of the disk forms

a wedge which bears against the rear side of the standard or downturned rear portion of the beam, relieves the adjusting-bolt 6 of strain, and supports the said beam when adjusted. Prior to the adjustment of the beam the same may be predetermined by turning the disk 8 to the requisite extent, the bolt 6 being tightened after the beam has been adjusted. It will be understood that the adjusting-bolt 6 and cam-disk 8 coact to set and hold or retain the beam at any required adjustment. It will be observed by reference to the drawings that the front side of the disk 65 8, by reason of its being provided with the cam 10, is heavier than the rear side thereof and that the cam tends by gravity to work downward against the rear side of the standard or downturned rear portion of the beam, 70 and hence to counteract any tendency of the bolt 6 to work loose.

I do not desire to limit myself to the precise construction and combination of devices herein shown and described, as modifications may 75 be made therein without departing from the spirit of my invention.

While the cam forms a wedge that bears against the rear side of the standard portion of the beam, another form of wedge might be 80 employed in lieu of the cam for the same purpose, as is evident. Other suitable means may, within the scope of my invention, be employed to brace the standard and relieve the adjusting-bolt of stress, and I do not limit 85 myself in this particular.

Having thus described my invention, I claim—

1. The combination of a plow having an adjusting-slot, a beam having its standard portion pivoted to the plow so that the front end of the beam may be raised and lowered, an adjusting-bolt transversely disposed in said beam and working in said slot, and a revolvable disk mounted in rear of the beam-standard 90 and having an eccentrically-disposed cam on its front side bearing against the rear side of the standard portion of the beam, said cam-disk and adjusting-bolt coacting to secure the beam at any required adjustment, and said 95 cam-disk relieving said adjusting-bolt of stress, substantially as described.

2. The combination of a plow, a beam pivoted thereto, and thereby rendered capable

of adjustment so that the front end of the beam may be raised and lowered, an adjusting-bolt, extending transversely through the standard portion of the beam and through the plow, and a cam bearing against the rear side of the standard portion of the beam, said cam and bolt coacting to secure and adjust the beam, and said cam relieving said adjusting-bolt of stress, substantially as described.

10 3. The combination of a plow, a standard pivoted thereto, for the purpose set forth, an adjusting-bolt transversely disposed in the plow and standard and connecting the same together, and a cam bearing against the rear 15 side of the standard and relieving the said

adjusting-bolt of lateral stress, substantially as described.

4. The combination of a plow, a standard pivoted thereto, for the purpose set forth, an adjusting-bolt to secure said plow and standard together, and means to brace said standard and thereby relieve said adjusting-bolt of stress, substantially as described.

In testimony that I claim the foregoing as my own I have hereto affixed my signature in the presence of two witnesses.

PETER MCNAUGHTON.
